DESIGN FOR A DISPLAY PLATE FOR USE ON AUTOMOBILES

Abraham Plotkin, Buffalo, N. Y.

Application December 12, 1941, Serial No. 104,601

Term of patent 3½ years

To all whom it may concern:

Be it known that I, Abraham Plotkin, a citizen of the United States, residing at Buffalo, in the county of Erie and State of New York, have invented a new, original, and ornamental Design for a Display Plate for Use on Automobiles, of which the following is a specification, reference being had to the accompanying drawing, forming a part thereof.

In said drawing:

Figure 1 is a front elevational view of a display plate for use on automobiles embodying my new design;

Figure 2 is a vertical section taken along line 2—2 of Figure 1;

Figure 3 is a top view of the display plate for use on automobiles; and

Figure 4 is a horizontal section taken along line 4—4 of Figure 1.

I claim:

The ornamental design for a display plate for use on automobiles, substantially as shown.

ABRAHAM PLOTKIN.
